UNITED STATES PATENT OFFICE.

HENRY PITT ROBERTS, OF BOSTON, MASSACHUSETTS.

APPARATUS FOR SANDING ROADS.

1,025,646.

Specification of Letters Patent.

Patented May 7, 1912.

Application filed August 13, 1910. Serial No. 577,115.

To all whom it may concern:

Be it known that I, HENRY Pitt Roberts, a citizen of the United States, residing in Boston, in the county of Suffolk and 5 State of Massachusetts, have invented certain new and useful Improvements in an Apparatus for Sanding Roads, of which the following, taken in connection with the accompanying drawings, is a specification.

10 This invention relates to an apparatus for spreading sand on roads.

The object of the invention is to provide an apparatus for spreading sand evenly over a large area.

15 The device is primarily intended for use in spreading sand over the surfaces of roadways which have been previously coated with oil, tar, or similar substances in an adhesive or sticky condition.

20 With the above object in view, the apparatus comprises a vehicle which is adapted to follow the wagon which applies the liquid to the roadway, and is provided with means for discharging the sand in a broad stream or sheet evenly over the coated surface of the roadway. This sanding vehicle may be attached to the rear of the liquid-carrying vehicle, or it may be self-propelled. It is impossible to draw the sanding 25 appliance by horses attached directly thereto, for the reason that their feet would become greatly fouled by the liquid on the road; so that the preferred embodiment of the invention comprises a self-propelled vehicle, although it is not limited thereto.

30 The invention consists in the sanding apparatus hereinafter described and claimed, the advantages of which will be obvious to those skilled in the art from the following description.

35 In the accompanying drawings Figure 1 is a side-elevation of the apparatus, Fig. 2 is a front elevation of the same, partly in section, Fig. 3 is a sectional elevation taken 40 on the line 3-3 in Fig. 4, and Fig. 4 is a plan view of the apparatus.

45 As illustrated in the drawings the apparatus comprises a wagon body 1 pivotally supported at 2 upon the front frame 3, to 50 which the steering axles are connected upon which the front wheels 4 are mounted. The purpose of thus pivotally mounting the body 1 is to enable it to be tilted as shown by the dotted lines in Fig. 3, to facilitate 55 the forward feeding of the sand, as will be hereinafter explained. The rear end of the

body 1 is supported on the rear axle 5 upon which the rear wheels 6 are mounted. These wheels are provided with wide tires and their gage is substantially that of 60 ordinary wagons or motor vehicles. The front wheels 4 may be gaged so that the outer edges of their tires are substantially in line with the inner edges of the tires on the rear wheels. Thus as the vehicle moves 65 over the road it rolls a comparatively wide track in the sand which has been spread, and thus aids in forming a smooth, finished surface.

70 The vehicle may be propelled by any suitable motor 10 connected by sprocket chains 11 to sprocket wheels 12 on the rear wheels 6. The front wheels 4 are steered by the hand wheel 14 in front of the seat 15. This hand wheel is mounted on a shaft 16 which 75 carries an arm 17 pivotally connected by a crank arm 18 to a rod 19, which in turn is pivotally connected to a crank arm 20 on the upper end of a shaft 21 journaled in a bracket 22 secured to the wagon body. A 80 crank arm 23 is secured to the lower end of the shaft 21 and is pivotally connected to one end of a rod 24, which in turn is pivotally connected to the steering knuckle 25 of the front axle. 85

90 The sides of the body are flared at 30 and 31 to increase the width of the body at the front end. Said body is divided by a transverse partition 32 into a sand compartment 33 and a brush compartment 34. 95 An opening 35 extends through the lower edge of the partition 32 to enable the sand to pass from the sand compartment to the brush compartment. The amount of sand fed through this opening may be regulated by a slide 36 mounted upon the front side of the partition 32. This slide is controlled by a handle 37 secured to a shaft 38 and having a sliding rod 39 adapted to engage 100 a toothed sector 40 to hold the handle 37 in an adjusted position. A crank arm 41 is secured to the other end of the shaft 38 and is connected by a link 42 to a crank 43 on a shaft 44 extending the length of the brush compartment. A pair of crank arms 45 are secured to this shaft and connected by 105 links 46 to brackets 47 on the slide 36. By moving the handle 37 forward or backward the slide 36 may be lowered or raised as desired, and then held in adjusted position 110 by the engagement of the rod 39 with the rack 40.

A brush 50 is journaled to rotate in suitable bearings and extends from one side to the other of the brush compartment 34. The brush is rotated clockwise, as viewed in Fig. 3, and discharges the sand in the form of a wide sheet or stream through the opening 51 extending along the lower edge of the front 52 of the brush compartment. The brush is driven by a sprocket wheel 53, adjacent to the sprocket wheel 12, by a chain 54 coöperating with a sprocket on a shaft 55 which carries a bevel gear 56. The bevel gear 56 meshes with a bevel gear 57 on one end of a shaft 58, having a bevel gear 59 at its other end. The bevel gear 59 meshes with a bevel gear 60 on a shaft 61 which is provided with a bevel gear 62 slidably mounted thereon and meshing with a bevel gear 63 on the brush shaft 64. The brush 20 may be thrown into or out of action by a handle 66 connected to a shaft 67 which is provided with a crank arm 67^a connected by a link 68 to one end of a lever 69, the other end of which is connected to a grooved 25 boss on the gear 62. A rod 70 on the handle 66 engages a rack 71 to hold the handle in adjusted position.

The rear end of the body 1 is raised and lowered by the following mechanism. A screw 80 is pivotally supported upon rear axle 5 and projects through the bottom of the body about midway thereof. A casing 81 covers the screw to prevent the sand from gaining access thereto. A nut 82 is threaded 35 on the screw and formed with a worm wheel 83 which meshes with a worm 84 on a rod 85 mounted in bearings in the bottom of the body. The nut 82 bears against a plate 86 on the bottom of the body, and as the nut 40 rotates the body is raised or lowered. The rod 85 is provided with a bevel gear 87 which meshes with a bevel gear 88 on one end of a shaft 89, the other end of which is provided with a sprocket wheel engaging 45 a chain 90 coöperating with a sprocket wheel 91 on one end of a shaft 92, the other end of which is provided with a crank handle 93. By turning the handle 93 the nut 82 is rotated by means of the mechanism just 50 cited.

From the description above set forth it will be seen that the wagon body may be inclined as desired to feed the sand toward the brush, and the amount of sand fed into the brush compartment can be regulated, thus regulating the discharge through the opening in the front of the machine, and

all of the mechanism can be operated from the seat.

While I have illustrated and described a preferred embodiment of the invention, I am aware that many modifications can be made therein by any person skilled in the art without departing from the scope of the invention as expressed in the claims. Therefore I do not wish to be limited to all the details of construction shown and described, but

What I claim is:—

1. In an apparatus for sanding roads, the combination of a wagon body having a sand compartment and a brush compartment, a brush mounted to rotate in the brush compartment, a seat at the front of the body, means operable from the seat for raising the rear end of the body, and means through which the sand is discharged by the brush. 70

2. In an apparatus for sanding roads, the combination of a wagon body widened toward its front end and provided with a discharge opening, a sand compartment in the rear portion of the wagon body, a seat on the wagon body, means operable from the seat for raising the rear end of the body to facilitate the feeding of the sand from the sand compartment, and means controlled from the seat for regulating the amount of sand delivered from the sand compartment. 80

3. In a device of the character described, the combination of a running gear, a vehicle body mounted upon the running gear and having one end thereof flared laterally so as to project beyond the running gear, a brush compartment being formed in the flared end of the vehicle body and the said brush compartment communicating with the vehicle body and being provided with a discharge slit, a brush mounted within the brush compartment for forcing material through the discharge slit, gearing between the running gear and the brush, a seat upon the vehicle body, means operable from the seat for throwing the said gearing into and out of action, and means also operable from the seat for tilting the vehicle body to cause material in the same to flow into the brush compartment. 90

In testimony whereof I have signed this specification in the presence of two subscribing witnesses.

HENRY PITT ROBERTS.
